UNITED STATES PATENT OFFICE

2,463,539

MAGNETIC FREQUENCY MULTIPLIER

Henry M. Huge, Lorain, Ohio, assignor, by mesne assignments, to Lorain Products Corporation, Lorain, Ohio, a corporation of Ohio

Application May 5, 1945, Serial No. 592,095

9 Claims. (Cl. 172—281)

1

This invention relates to magnetic frequency multipliers and in particular to an arrangement for repeated doubling of a given input frequency by a cascade connection of magnetic frequency doublers.

Magnetic frequency changers made up of cascade-connected frequency doublers have been known for many years. In particular, such arrangements have been described by Georg Von Arco and Alexander Meissner in U. S. Patents No. 1,181,556, No. 1,267,018 and No. 1,308,514.

Numerous difficulties have been encountered in the operation of frequency doublers in this manner, and the difficulties increase with the number of stages cascaded. One of the chief problems lies in the tendency for a voltage component of the input frequency to appear in the output of the frequency doublers when they are operated in cascade. Other difficulties result from the variations in tuning requirements which result from load current variations.

By my invention, both of these difficulties are overcome and it is possible to cascade a large number of frequency doubling stages and to supply a greatly increased frequency to a variable load such as an induction motor. Furthermore, my invention eliminates the need for precise tuning of the cascaded circuits and therefore facilitates the energization of variable loads.

To accomplish these results, my frequency changer utilizes a polyphase frequency changing arrangement such as that shown in my U. S. patent application Serial No. 535,480 filed May 13, 1944, now U. S. Patent No. 2,395,389, issued February 26, 1946. In this arrangement, the outputs of frequency doublers energized from input phases 90° displaced are combined. The 90° displacement of the input voltages results in a 180° displacement at the doubled frequency and an in-phase relationship at all even harmonics of the doubled frequency. The outputs are combined so that all even harmonics of the output frequency are substantially eliminated by cancellation.

I have found that this output voltage, which is substantially free of even harmonics, may be supplied to another frequency doubler directly without encountering the difficulties previously mentioned. There is no tendency for components of undesired lower frequencies to appear in the output of the second stage of the frequency doubler. Furthermore, if the second stage is similar to the first and the even harmonics are again eliminated, a third stage may be energized from it, and so on for additional stages until the required frequency is attained.

2

It is an object of my invention to obtain a large increase in frequency by a cascade arrangement of magnetic frequency doublers.

Another object of my invention is to provide a polyphase output of a greatly increased frequency.

Still another object is to eliminate components of the input frequency from the output voltage of a frequency doubler.

10 An additional object of my invention is to supply the biasing current for a cascade arrangement of frequency doublers from a common biasing source and to control the current in response to biasing requirements.

15 Other objects and a better understanding of my invention may be obtained by referring to the following specification and claims in connection with the accompanying drawings in which

Figure 1 shows a three-legged saturable reactor having a center-tapped primary winding as utilized in my invention,

20 Figure 2 shows a second type of reactor with an untapped primary winding,

25 Figure 3 shows a somewhat different reactor which may be used for the same purposes as the reactors shown in Figures 1 and 2,

Figure 4 shows still another combination which may be used in place of the reactors of Figures 1 and 2, and

30 Figure 5 is a schematic diagram showing how a number of reactors such as those shown in Figures 1 and 2 may be interconnected in one embodiment of my invention.

With more particular reference to Figure 1, 35 there is shown a three-legged magnetic core structure 16, having a primary winding 11 on the central core member, and secondary windings 14 and 15 with direct current windings 12 and 13 on the two outer core members. The primary winding 11 is provided with a center tap 17. The secondary windings 14 and 15 are phased non-inductively with respect to the primary winding 11. The D. C. windings 12 and 13 are phased in the same polarity as the secondary windings.

40 45 With this arrangement, a flow of direct current produces a unidirectional flux in the two outer members of core 16. Alternating current applied to the primary winding 11 produces unequal fluxes in the outer core members because of the saturating action of the unidirectional flux. The unequal division of fluxes reverses with the polarity of the primary alternating current cycle and the resultant induced secondary voltage is of twice the primary frequency.

50 55 The structure of Figure 2 is similar to the struc-

ture shown in Figure 1 and comprises a three-legged magnetic core 26, having primary winding 21 on its central member and secondary windings 24 and 25 together with direct current windings 22 and 23 on its outer members. It differs from Figure 1 in that the center tap 17 shown in Figure 1 is omitted in Figure 2.

In the three-legged reactor shown in Figure 3 the primary windings 34 and 35 are wound on the two outer core members and the secondary winding 33 and the D. C. winding 32 are wound on the central core member. The primary windings are polarized non-inductively with respect to the secondary winding. Direct current through the D. C. winding 32 produces unidirectional flux in the outer core members, causing the primary A. C. flux to divide unequally between the outer members. As described in connection with Figure 1, the resultant induced voltage in the secondary winding is of twice the primary frequency.

Figure 4 shows still another alternate arrangement of frequency doubling reactors. In Figure 4, two separate transformers are used, with their primaries 36 and 37 connected in series, and secondaries 40 and 41 and also direct current windings 38 and 39 connected in series opposition with respect to the primary windings so as to be non-inductively arranged with respect to the primary. As in the arrangements of Figures 1, 2 and 3, the unequal reaction to primary magnetization produced by the unidirectional flux in the magnetic flux paths produces an induced voltage of twice the primary frequency in the secondary circuit.

Figure 5 shows schematically the arrangement of a number of reactors of the types shown in Figures 1 and 2 in a cascade arrangement of frequency doublers for supplying a three-phase output of four times the source frequency.

The first stage of the frequency changer is shown in the upper portion of the drawing and the second stage below it. The first stage utilizes three reactors of the type shown in Figure 1 and three of the type shown in Figure 2. The first three reactors are designated A, B and C and may be considered as a first polyphase frequency doubler while the second three are designated D, E and F and may be described as a second polyphase frequency doubler.

This pair of three-phase frequency doublers is connected to the three-phase source 10 and the two doublers are arranged to have 90° phase displacement between their energizing voltages.

The windings in Figure 5 are designated by the same reference numbers as the corresponding windings in Figures 1 and 2. To each number there is affixed a letter indicating which of the reactors carries the winding in question, with each reactor designated by a letter as previously mentioned.

Interconnections of the windings in the first stage are shown diagrammatically in the upper portion of Figure 5 with the primary connections on the left side of the diagram, the D. C. connections in the center, and the secondary connections on the right side of the diagram. The positioning of the primary coils indicates the phases of the primary voltages.

The primary windings of the reactors D, E and F are energized 90° out of phase with the primaries of A, B and C. The phase displacement is accomplished as shown in Figure 5 through the use of the center taps 17 on the primary windings 11.

The direct current windings 12 and 13 of each

5 of the reactors A, B and C are connected in series and connected to the output of the rectifiers 48. Similarly the direct current windings 22 and 23 of each of the reactors D, E and F are connected in series and connected to the rectifiers 48. The voltages in these series circuits approximately cancel each other so that they impress very little alternating current on the rectifiers 48. In some cases it may be desirable to 10 by-pass alternating current around the rectifiers. In such cases, capacitor 27, connected across the direct current terminals of the rectifier, is included.

The rectifiers 48 are energized from the secondaries 45, 46 and 47 of current transformers whose primary windings 42, 43 and 44 are connected in series with the input to the frequency multiplier. The current transformers may be wound on a common three-phase core and I prefer to connect the secondary windings 45, 46 and 47 in delta as shown, in order to short-circuit the third harmonic voltage and keep down the peak inverse voltage on the rectifiers 48.

The secondary connections of the first stage 25 of the frequency multiplier are shown in the upper right hand portion of Figure 5. In Figure 5, the secondary circuits of each two reactors whose primary circuits are energized 90° out of phase with each other are connected in series. 30 The windings are polarized so that the double frequency voltages appearing in the windings add together. This is possible because a 90° displacement at the fundamental frequency results in 180° displacement at the second harmonic 35 frequency. Thus the secondary windings 14 and 15 of reactor C are connected in series with the secondary windings 24 and 25 of the reactor F to supply one phase of the three-phase output. Similarly, the windings 14A and 15A in series with 24D and 25D supply the second phase, and 14B and 15B in series with 24E and 25E supply the third output phase. Figure 5 shows these output phases delta-connected, although a star connection could be used.

45 Capacitors 29, 30 and 31 are connected one across each of the output phases and are energized by the three-phase voltage of twice the frequency of source 10. They are used to aid in the excitation of the double frequency.

50 As previously mentioned the 90° phase displacement between primary voltages results in a 180° displacement between secondary voltages of twice the source frequency. The phases between voltages of even multiples of twice the source frequency are even multiples of 180° or integral multiples of 360°. Therefore, when the secondary windings are polarized to add voltages of twice the source frequency all even harmonics of twice the source frequency are cancelled, although odd harmonics may remain.

55 The second stage of the frequency multiplier is shown in the lower portion of Figure 5 and comprises three more reactors G, H and J like that shown in Figure 1 and three more reactors K, L and M like that shown in Figure 2.

The primary connections of the second stage are shown in the lower right hand portion of Figure 5, the direct current connections in the center and the secondary connections in the lower left hand portion of Figure 5.

70 The second stage of the frequency multiplier is similar to the first stage except that it does not include its own biasing source: i. e. current transformers and rectifiers. The direct current windings 12 and 13 of the reactors G, H and J are

connected in series in the same manner as the windings 12A, 13A, 12B, 13B, 12C and 13C of the first stage. Likewise the windings 22 and 23 of the reactors K, L and M are connected in series in the same manner as the windings 22 and 23 of the reactors D, E and F. The sets of direct current windings are connected in parallel to the output of the three-phase rectifiers 48. Although the second stage of the multiplier might be provided with its own current transformers and rectifiers, the economical advantages of the arrangement shown are obvious.

The primary windings 11 of the reactors G, H and J are connected in parallel with the capacitors 29, 30 and 31. The primary windings 21 of the reactors K, L and M are energized 90° out of phase with the windings 11 by means of the center taps 17G, 17H and 17J.

The secondary windings 14, 15, 24 and 25 of the reactors G, H, J, K, L and M are connected in the same manner as the secondary windings of the reactors A, B, C, D, E and F. Thus, again, the even harmonics of the output voltage are cancelled.

The capacitors 18, 19 and 20 are connected across the three phase output of four times the frequency of source 10 and aid in the excitation of the output voltage.

The operation of the second stage of the frequency changer is similar to that of the first stage as already described.

The common biasing arrangement produces comparable biasing conditions in both the first and second stages of the frequency changer. When a load is connected to the output of the frequency changer, its effect is reflected in the input current which flows through the primary windings 42, 43 and 44 of the current transformers; consequently, the biasing current is adjusted by the load condition. I prefer to cause the current transformers to become saturated under heavy input currents, so that the biasing currents which flow under this condition are limited to their optimum values.

The load on the output of the second stage of the frequency multiplier may be an induction motor or other three-phase load, or it may comprise another stage of frequency multiplication, doubling or tripling as may be required. I have found that as long as the even harmonics are kept out of the voltages, no difficulty is experienced in cascade operation of the frequency doublers, but if even harmonics appearing in the output voltage of one stage of the frequency multiplier are fed into the following stage, the difficulties mentioned earlier immediately arise. In particular, the balancing action of the reactors is described in connection with Figures 1 and 2 is no longer perfect and the secondary windings receive induced voltage of the frequency which is applied to the primary windings.

When a load which is not sensitive to the presence of even harmonics is being supplied, the last stage of the frequency multiplier may be simplified by omitting the reactors K, L and M and supplying the load with the voltage which includes some even harmonic distortion. Likewise, when a single-phase output is required, the number of reactors may be reduced.

Although I have described my invention with a certain degree of particularity, it is understood that the present disclosure has been made only by way of example and that numerous changes in the details of construction and the combination and arrangement of the parts may be made

without departing from the spirit and scope of the invention as hereinafter claimed.

I claim as my invention:

1. A frequency multiplier comprising a plurality of cascaded frequency multiplying stages, the first stage comprising first and second frequency doublers, means for energizing said first doubler with an alternating voltage and means for energizing said second doubler with an alternating voltage displaced substantially ninety degrees from the voltage energizing said first doubler, the output voltages of said first and second doublers being combined and connected to a second frequency multiplying stage to supply it with an input voltage substantially free of even harmonics.

2. A frequency multiplier comprising a plurality of cascaded frequency multiplying stages, each of said cascaded stages being adapted to be energized with voltage substantially free of even harmonics from the preceding stage, said voltage substantially free of even harmonics being obtained from a balanced frequency doubling stage, said balanced stages each comprising first and second frequency doublers, means for energizing said first doubler with a first alternating voltage, and means for energizing said second doubler with a voltage substantially ninety degrees out of phase with said first voltage, said first and second doublers supplying output voltages with additive fundamental components and cancelling even harmonic components.

3. In combination with a biased-core magnetic frequency multiplier comprising a plurality of cascade-connected stages, controlled biasing means comprising a current transformer and a rectifier, said rectifier being adapted to supply biasing current to at least two of said stages, the primary of the current transformer being energized with the input current to the frequency multiplier, the secondary being connected to the rectifier.

4. In combination with a biased-core magnetic frequency multiplier comprising a plurality of cascade-connected stages, controlled biasing means comprising a current transformer and a rectifier, said rectifier being adapted to supply biasing current to at least two of said stages, the primary of the current transformer being energized with the input current to the frequency multiplier, the secondary being connected to the rectifier, said current transformer having a magnetic core which decreases in permeability with increasing flux density within the normal range of operating flux densities.

5. A polyphase frequency multiplier adapted to be energized by a polyphase A. C. source and to supply a polyphase output, comprising in combination a plurality of cascade-connected stages, each stage comprising, in combination, saturable magnetic core means, biasing means for producing unidirectional flux in said core means, primary and secondary circuit means comprising windings on the core means, and polyphase capacitive means connected to the secondary circuit means, said primary and secondary circuit means being noninductively arranged on the core means, secondary voltage of twice the primary frequency being produced by the effect of the unidirectional flux on the saturable core means with voltage of the primary frequency being substantially balanced out of the secondary circuit means, each phase of the polyphase output being supplied from a portion of the secondary circuit means which is energized from a plurality of primary windings

adapted to be energized from a plurality of primary phases which induce secondary voltage of the secondary output frequency in substantially the same phase and induce secondary voltages of even harmonics of the secondary frequency in opposing phases to substantially balance even harmonics out of the secondary output voltage.

6. In a frequency multiplier having a plurality of cascaded stages at least one of which utilizes biased magnetic core means, circuit means for supplying each of said cascaded stages with voltage substantially free of even harmonics, said circuit means comprising at least one balanced frequency doubling stage utilizing said biased magnetic core means, said balanced stage comprising a pair of frequency doublers, means for energizing one of said doublers with a first alternating voltage and means for energizing the other of said doublers with an alternating voltage substantially ninety degrees out of phase with said first voltage, said doublers supplying output voltages with additive fundamental components and cancelling even harmonic components.

7. A three-phase frequency multiplier comprising in combination a plurality of cascade-connected stages, each stage comprising, in combination, six saturable reactors each having two magnetic flux paths with primary and secondary windings thereon, the primary windings being adapted to be energized with polyphase alternating current to magnetize both magnetic flux paths of each reactor, the secondary windings being non-inductively wound on the two flux paths of each reactor with respect to the primary windings, biasing means adapted to produce unidirectional flux through the flux paths causing them to react unequally to primary magnetization and thereby to induce in the secondary windings voltage of twice the source frequency, the secondary of each reactor being connected in series with the secondary of another reactor, with substantially ninety degrees phase displacement between the primary voltages of the two reactors.

8. A frequency multiplier comprising a plurality

of cascaded stages in combination with biasing means for said stages, each of said stages comprising a pair of three-phase doublers adapted to operate with substantially ninety degrees phase displacement between their energizing voltages to provide in-phase outputs at twice their energizing frequency and substantially cancelling outputs at even harmonics of twice their energizing frequency, said three-phase doublers comprising saturating magnetic core means, said biasing means comprising a rectifier connected to the secondary of a transformer whose primary is connected in series with the input to said frequency multiplier.

15. 9. A frequency multiplier comprising a plurality of cascaded stages in combination with biasing means for at least one of said stages which comprises a pair of three-phase doublers adapted to operate with substantially ninety degrees phase displacement between their energizing voltages to provide in-phase outputs at twice their energizing frequency and substantially cancelling outputs at even harmonics of twice their energizing frequency, said three-phase doublers comprising saturating magnetic core means, said biasing means comprising a rectifier connected to the secondary of a transformer whose primary is connected in series with the input to said pair of frequency doublers.
